UNITED STATES PATENT OFFICE

CROSBY FIELD, OF BROOKLYN, NEW YORK

METAL GRILLE

Application filed May 16, 1929. Serial No. 363,470.

My present invention concerns more particularly grilles, specifically in the form of open mesh fabric woven, preferably by machinery, from more or less flattened metal strips or wire.

When woven by any standardized method, particularly by machine, the present-day product has a very uniform, machine-made appearance, and one object of my present invention is to break up the hard lines and machine-like regularity of the grilles by making the flattened metal strips varying in width from end to end, preferably combining therewith a variation in thickness. The variation in width tends to give the completed grille a pleasing variation, by reason of the juxtaposition of the varying outline. There may be also a tendency to slight lateral shift of the individual wires by reason of the non-uniformity of widths and this is further accentuated when the wire is also of varying thickness.

My invention may be more fully understood from the following description in connection with the accompanying drawing, in which

Fig. 1 is an edge view of one of the strips;

Fig. 2 is a view of the convex or exposed face of the strip;

Fig. 3 and 4 are cross-sectional views respectively on the lines 3—3, 4—4, Fig. 1;

Fig. 5 is a view of the flat face of a modified form of strip;

Fig. 6 is a cross-sectional view on the line 6—6 of Fig. 5; and

Fig. 7 is a view of a grille made from strips having the characteristics illustrated in the preceding figures.

All of these views are more or less diagrammatic and in general the characteristic variation in width or edge outline is exaggerated. Moreover, the variation and thickness may be very much less than indicated in any of the views.

In the specific form shown in Figs. 1 and 2, the strip is supposed to be flat on the top surface, as indicated by the edge view of Fig. 1 and convex on the other surface as indicated in Fig. 2. This convexity may be and preferably is the true cylinder surface presented

by drawn wire, and the flat surface is achieved by shaving, and while this is preferable it will be evident that strips having one or all of the same characteristics may be made by drawing or rolling. As shown in Figs. 3 and 4 the flat surfaces are substantially chords and the curved surfaces substantially arcs of the same circle, the thick portion 1 is about twice the thickness of the thin portion 2, and the wider portion 3 and narrower portions 4 are produced by reason of the varying points at which the flat surface intersects the cylinder of the wire. It will be understood that while it is desirable, it is not necessary that the wide portions coincide with the variations of thickness nor that the convex surface be a true cylinder.

Strips having the above characteristics are shown in Fig. 7 as woven in one of the many patterns that may be selected to suit the artistry of the designer. The simple pattern in this case is warp strips a, a, a, woof strips b, b, b and diagonals c, c, c, and d, d, d. The thicker, wider portions 3, and the thinner, narrower portions 4 are shown as presented toward the observer, as in Fig. 2, but it is evident that the reverse side of the grille may be presented outward, and this is desirable, particularly where the edges 3, 4, are sharp, the convex surfaces being less likely to cause damage to person or apparel by accidental contact therewith.

A special form of strip that has very pleasing artistic as well as mechanical advantages, is more or less diagrammatically indicated in Fig. 5. Here the strip consists of wire that has been shaved to produce wool and the shaving has proceeded down to scrapping thickness, which is usually even less than indicated in Figs. 5 and 6.

If desired, the edges of the scrap from which the strips are made may be smoothed or slightly rounded and, if desired, the strip may be re-rolled to decrease the sharpness of the grooves or to eliminate them altogether.

In this modification even more than in the form first described, the length and pitch of the curved surfaces and edges and the total variation between maximum and mini-

mum thicknesses and widths may be modified within wide limits. Where the curves are very long and the slope small as compared with the size of the grille made therefrom, the irregularity may in the case of a single grille appear to the eye mainly as a variation of width which is continuous so far as concerns the portion of a single strip. Even in the case of almost imperceptible variations, the hand-made appearance will be evident.

I claim:—

1. A grille comprising interwoven spaced apart, spring metal strips that are of greater width than thickness, of gradually varying widths and thicknesses, the lengths of the variable portions of the strips being great as compared with the spacing of the strips.
2. A grille comprising interwoven metal strips that are of greater width than thickness, of varying widths and thicknesses, having one face substantially chords and another substantially arcs of the same circle.
3. A grille comprising interwoven metal strips that are of greater width than thickness, of varying widths, having one face substantially flat and another cylindrical, flat surfaces of one strip engaging cylindrical surfaces of another strip at all contact points of the strips, throughout the grille.
4. A grille comprising interwoven metal strips that are of greater width than thickness, said strips comprising longitudinal portions of cylindrical wire and having one face substantially flat but finely grooved longitudinally and another face substantially cylindrical, all grooved surfaces being presented toward the same face of the grille.
5. A grille comprising interwoven spring steel ribbons having substantially the size, shape and cross-section of the wire scrap from the metal wool cutting machine, said ribbons having one face conforming to chords and the other face conforming to arcs of the same circle, the chord face being longitudinally grooved and the ribbons having variations in thickness, from end to end, which are very small as compared with the mesh spacing of the ribbons as woven in the grille.

Signed at Brooklyn in the county of Kings, and State of New York, this 13th day of May, A. D. 1929.

CROSBY FIELD.
